HEEL MACHINE

Fred Ashworth, Wenham, Mass., assignor to
United Shoe Machinery Corporation, Paterson, N. J., a Corporation of New Jersey

Application February 5, 1931. Serial No. 513,591

10 Claims. (Cl. 12—50)

This invention relates to heel machines, and is herein shown as embodied in a machine for use in applying a rand to a lift, to form a base for a rubber heel, and trimming off the ends of the 5 rand which project beyond the breast edge of the lift.

It is an object of the invention to provide an improved machine which will perform one or both of the stated operations speedily, accurately and economically, and will turn out a uniformly excellent product.

In the building of heel bases it is customary to fit upon the marginal portion of one face of a heel lift an adhesively coated rand, to secure 15 the rand and lift together by pressure or otherwise, and then to trim off, as nearly flush with the breast face of the lift as possible, the projecting ends of the rand which is always somewhat too long since it is impracticable to use 20 rands of exactly the right length because of unavoidable variations occurring when the rands are bent or turned into the necessary curved shape. Heretofore the trimming of the ends of the rand has usually been performed either as a 25 separate operation or by a knife and cutting block embodied in the heel building machine in which the heel base was manufactured. More or less difficulty has been experienced in securing an accurate, clean cut, by reason of the knife 30 and cutting block arrangement and insufficient provision for supporting and holding the blank while the ends of the rand were being trimmed. In one type machine which has been used for this work the trimming knife is stationary and the 35 blank, often insecurely held, is moved past the knife to effect the trimming operation with results that are not always accurate and uniform.

The present invention provides an improved heel machine organization in which a heel support and a presser movable into engagement with a heel upon said support are combined with a trimming blade movable past the breast of a heel upon the support and means under the control of the presser for moving the trimming blade.

45 By virtue of this improved organization it becomes possible, although the trimming is performed entirely automatically as a part of each cycle of operation of the machine, to insure that the blank be firmly held under pressure prior to 50 and during the trimming operation.

In order to obtain a superior product in which the breast ends of the rand are uniformly trimmed smoothly and accurately a shear couple is preferably employed and, in accordance 55 with another feature of the invention, one shear

member is made movable with the presser and a shear blade is arranged to move past the breast end of the heel support into co-operative relation with said shear member to effect the trimming of the rand.

In the illustrated embodiment of the invention accurate positioning of the blank is insured by the provision of a heel form in which the rand and lift may be placed and which insures that their relation to the shear couple will always be uniform. Preferably, and as shown, the heel form is open at the breast to permit the breast ends of the rand to project therefrom while the blank is held rigidly stationary in the form and the shear couple operates to cut off the breast ends 70 of the rand.

In order to secure accurate and clean cutting, means may, in accordance with the invention, be provided for positioning one of the shear elements accurately and definitely to co-operate 75 with the other shear element in the operative movement of the latter.

In order to obviate the difficulty which is sometimes experienced in removing heel blanks from machines in which they have been subjected to pressure the invention also includes an improved ejector mechanism for quickly removing the completed blank from the heel form. In the present instance the ejector is operated by a spring which is energized by relative movement 80 of the presser and heel form away from pressure exerting position and is automatically released at the proper time to permit it to operate upon the completed blank when the pressure is 85 removed therefrom.

These and other features and advantages of the invention will best be understood and appreciated from reading the following detailed description of one satisfactory embodiment thereof 95 in connection with the accompanying drawings, in which

Fig. 1 is a view in side elevation of a machine embodying the invention;

Fig. 2 is a front elevation of the machine;

Fig. 3 is a plan view, partly in section; and

Fig. 4 is a vertical, central section from front to rear of the parts of the machine which operate upon the blank.

The operating mechanism of the machine is mounted in a frame 10 and is similar in its general organization to that of the heel building machine disclosed in United States Letters Patent No. 1,056,720, granted March 18, 1913, upon application of Eliphalet A. Tripp.

Upon a stationary table 12 are mounted a heel

support 14 and a heel shaped form 16 which is open at the breast, as is clearly shown in Fig. 3. When using the machine in the manufacture of heel bases a lift 18 is placed in the form 16 and 5 an adhesively coated rand 20 is fitted into the form on top of the lift.

In order to apply the necessary pressure to the rand and the lift to cause them to be secured together and to hold the blank while the projecting ends of the rand are trimmed off there is provided a presser 22 which is carried by a beam 24 similar to the beam 122 shown in the Tripp patent. As described in detail in the said patent the beam is capable of being swung about a pivot 10 26 in the forward end of a cam lever 28 which is operated at suitable times by a cam upon the main driving shaft 30 of the machine. The driving shaft 30 is rotated by power derived from a pulley 32 through a one revolution clutch 15 controlled by a bar 34 (see Fig. 1) pivotally connected at 36 to the beam 24, the construction and arrangement being such that when the presser carrying beam 24 is drawn forward to a position in which the presser 22 is over the heel form 16 20 the clutch is tripped and the cam lever 28 is actuated to depress the beam and the presser to apply pressure to the work in the form. As soon as the operation upon the blank is finished the presser is elevated by a spring 38 and the beam 25 is drawn back by a spring 40, leaving the space over the heel form unobstructed.

The presser 22 is carried by a presser head 24, to the front face of which is secured a shear member 42 having a lower work engaging edge which is 30 inclined upward from the center toward both ends as shown at 44 in Fig. 2. The shear member 42 is secured to the presser head 24 by bolts 46 passing through slots 48 in the shear member, to permit vertical adjustment of the latter so that the 35 lower edge 44 will engage firmly the upper face of the rand and lift when the presser 22 is lowered to pressure applying position. A screw 50 bearing against the upper edge of the shear member 42 serves to maintain the adjustment positively.

40 Movable past the open breast end of the heel form 16 into co-operative relation with the shear member 42 is a vertically guided shear blade 52 which is secured by screws 54, passing through slots 56 in the shear blade, to a plunger 58 operated by a toggle 60 corresponding to the toggle 186 of the machine shown in the Tripp patent. In the operation of the machine this toggle is actuated to raise and lower the plunger 58 after the presser 22 and shear member 42 have been 45 lowered into engagement with the blank in the heel form and while the said blank is rigidly held stationary in the form.

The upper edge of the shear blade 52 lies in a single horizontal plane and, by reason of the inclination of the lower edge of the co-operating shear member 42 in both directions from its center, the member 42 and the blade 52 constitute a shear couple operating as two oppositely directed pairs of shears to trim the two projecting ends of the rand accurately and cleanly, flush with the breast face of the lift to which the rand is secured. The upward inclination of the lower edge 44 of the shear member 42 from its center toward each side causes a progressive cutting action from the center outward, which has a peculiar advantage in that there is a decided tendency to force the end portions of the rand outward as the cutting progresses, thereby avoiding any danger that they will be misplaced inwardly relatively to the edges 50 of the lift.

The shear blade 52 is accurately guided vertically by straight guides 62 and, in order to insure perfect co-operation with the upper shear member 42, means is provided for positioning the latter very accurately in relation to the lower shear blade. As shown, heavy guide posts 64 are mounted rigidly in the machine frame in fixed relation to the heel support and guides 62. Heavy brackets 66 are secured to the beam 24 and have through them holes 68 which fit slidably upon the guide posts 64. The upper ends of the guide posts are tapered, as shown at 70, in order to guide the brackets 66 easily into interengagement with the posts and accurate positioning of the beam 24, and shear member 42 carried thereby, is assured when the beam is lowered to apply pressure to the work.

In order quickly and certainly to remove completed blanks from the machine after the trimming blade 52 has been lowered and the pressure upon the blank has been released, improved ejecting mechanism is provided. A horizontal ejector rod 72 is guided for sliding movement through an aperture 74 in the rear of the heel form 16. An expansion spring 76, surrounding the rod 72, bears at one end against the machine frame and at the other end against a collar 78 secured to the rod. The force of this spring tends at all times to project the rod 72 toward the front of the heel form, and a buffer 80 secured to the rear end of the rod limits the forward movement of the rod.

The spring 76 is energized by the movement of the presser carrying beam 24 away from pressure exerting position through the medium of a latch 82 pivoted in the beam 24 at 84. The lower end of the latch is bifurcated, embracing the rod 72 and engaging a pin 85 upon the said rod when the beam 24 is allowed to fall backward under the influence of the spring 40. A screw 86 threaded through the upper end of the latch 82 and bearing against the beam, as shown in Figs. 3 and 4, provides for adjustment of the position to which the lower end of the latch shall move and consequently of the amount by which the spring 76 shall be compressed. This adjustment is so regulated that the rod 72 will be retracted until a spring catch 88 can snap up in front of a shoulder 90 upon the rod and hold the rod retracted with the spring 76 under tension.

When the beam 24 is drawn forward manually to initiate the next operation of the machine the latch 82 swings loosely upon its pivot 84, the lower end of the latch riding freely over the spring catch 88 and dropping to the position illustrated in Fig. 4. After the machine has operated upon the blank, and as the presser beam 24 moves backward, the lower end of the latch 82 engages the upper face of the spring catch 88, tripping the catch and releasing the ejector rod 72 which is then suddenly projected forward by the spring 76, instantly ejecting the blank from the heel form and throwing it upon an inclined delivery chute 92 supported by a bracket 94 bolted upon the front of the machine. Continued backward movement of the presser beam causes the latch 82 to engage the pin 85 and again compress the spring 76 until the spring catch 88 engages the shoulder 90 and holds the ejector rod 72 retracted ready for the next operation of the machine.

Having described the invention, what is claimed as new and desired to be secured by Letters Patent is:

1. In a heel machine, the combination of a

150

- heel support, a presser movable into engagement with a heel upon said support, a trimming blade movable past the breast of a heel upon the support, and means under the control of the presser 5 for moving the trimming blade. 80
2. In a heel machine, the combination of a heel support, a presser movable into engagement with a heel upon the support, a shear member movable with said presser, and a shear blade 10 movable past the breast end of the heel support into co-operative relation with said shear member. 85
3. In a heel machine, the combination of a heel support, a presser movable into engagement 15 with a heel upon said support, a shear member carried by said presser, a shear blade movable into co-operative relation to said member, and means under the control of the presser for moving the blade. 90
4. In a heel machine, the combination of a heel form, a heel presser movable into engagement with a heel in said form, a shear member carried by said presser and movable into engagement with the heel simultaneously therewith, 25 and a shear blade movable past the breast end of the form into co-operative relation with said shear member. 95
5. In a heel machine, the combination of a heel-shaped form which is open at the breast 30 to permit the breast ends of a rand to project therefrom, a presser movable into the form to apply pressure to the rand, a shear member movable into engagement with the upper face of the rand to hold the ends of the rand against upward displacement, and a shear blade movable 35 upward past the breast end of the form and co-operating with said shear member to cut off the projecting ends of the rand. 100
6. In a heel machine, the combination of a heel-shaped form which is open at the breast to 40 permit the breast ends of a rand to project therefrom, a stationary heel support arranged to sustain a heel base blank in the form, pressure means for holding the blank rigidly stationary in the 45 105
- form upon said support with the breast ends of a rand projecting, and a shear couple operable in front of the form to cut off said breast ends of the rand while the blank is held rigidly stationary. 110
7. In a heel machine, the combination of a heel support, a presser movable into a position over said support, a shear blade movable past the breast of a heel upon the support, a shear member carried by the presser, and means for positioning the shear member accurately to co-operate with said blade when the latter is moved. 115
8. In a heel machine, the combination of a heel support a shear member movable into a position over said support, a shear blade movable past the breast of a heel upon the support, and means comprising relatively slidably interengaging elements rigid with said shear member and support, respectively, for positioning the shear member accurately over the support in co-operative relation to said blade when the latter is moved. 120
9. In a heel machine, the combination of a heel form, a presser movable to and from operative position relatively to the form to subject a heel blank to pressure, a heel ejector placed under spring tension by movement of the presser from operative position, and means for holding the ejector until pressure is applied to the heel blank and then freeing it to eject the heel when the pressure is removed. 125
10. In a heel machine, the combination of a heel form and a presser, means for relatively moving them into and away from position to exert pressure upon a heel blank in the form, an ejector placed under spring tension by relative movement of the presser and form away from a position to exert pressure, a catch for restraining movement of the ejector in response to the spring tension, and means for tripping the catch to release the ejector when the heel is subjected to pressure. 130
